UNITED STATES PATENT OFFICE.

JOHN R. WILLIAMS, OF EAST ORANGE, NEW JERSEY.

DESIGN FOR A NUT-LOCK.

SPECIFICATION forming part of Design No. 34,541, dated May 21, 1901.

Application filed February 7, 1901. Serial No. 46,447. Term of patent 14 years.

To all whom it may concern:

Be it known that I, JOHN R. WILLIAMS, a citizen of the United States, residing at East Orange, in the county of Essex and State of New Jersey, have invented and produced a new and original Design for a Nut-Lock, of which the following is a specification, reference being had to the accompanying drawings, forming a part thereof, and in which—
10 Figure 1 is a side elevation of a nut-lock bearing and incorporating my design. Fig. 2 is a top view of same, and Fig. 3 is a vertical section of same on the dotted line 3 3 of Fig. 1.

15 The leading feature of my design consists of the form and configuration of the nut-lock, substantially as shown.

In the drawings, A designates the nut-lock as a whole, said nut-lock being of spiral formation and having a substantially circular main body portion B and upwardly-extending arms C C, the latter being separated from one

another by an open space, as shown in Fig. 1, said open space breaking the line of the circle of the main body B. The arms C C ²⁵ merge on graceful lines into the main body portion B, as shown, and the rod composing the nut-lock is of substantially uniform character throughout and distinctive in that it has the curved outer surface D, the inwardly-³⁰ inclined surfaces E E, and the inner blunt edge F, the said surfaces D E F being continuous throughout the nut-lock. The surfaces E F in cross-section define substantially the outline of a truncated cone. ³⁵

What I claim is—

The design for a nut-lock, substantially as shown and described.

Signed at New York, in the county and State of New York, this 5th day of February, 1901. ⁴⁰
JOHN R. WILLIAMS.
